Inventor:
E. GROSSE
by
H. Gaudens, Jr.

UNITED STATES PATENT OFFICE.

EDUARD GROSSE, OF WACHEWITZ NEAR DRESDEN, GERMANY.

PRINTING MACHINE.

Original application filed May 5, 1921, Serial No. 467,187. Divided and this application filed June 9, 1922. Serial No. 567,233.

To all whom it may concern:

Be it known that I, EDUARD GROSSE, a citizen of Germany, and residing at Wachwitz near Dresden, Grundstrasse 8, Germany, have invented certain new and useful Improvements in Printing Machines, of which the following is a specification.

This invention is a divisional application from the parent application Ser. 467,187 filed May 5th 1921.

The present invention relates to a platen press which is simultaneously adapted to direct as well as indirect printing. Indirect or off-set printing was heretofore known only in connection with lithographic rotary and rapid printing machines. The present invention applies this method of printing to platen presses used in printing establishments for printing from composed type and cuts, and this application naturally required fundamental changes in the known type of platen presses.

Printing with the aid of the known type of platen presses was accomplished by pressing the workpiece by means of the hard surface of the platen directly onto hard surface of the form which usually consisted of metal. This required a very high pressure, necessitating the use of very strongly constructed machines.

According to the present invention, if the indirect method of printing is being employed, pressure is no longer directly exerted upon the hard form, but from the latter, by means of an elastic, preferably rubber-covered roller, a transfer is taking place to an elastic flat form against which the platen with the workpiece is being pressed whereby the transferred picture or composition is again being transferred from the elastic flat form to the workpiece or working sheet. By inserting this elastic flat form the amount of pressure needed is considerably reduced and even in the production of very large sheets only a slight pressure is needed.

The attached drawings indicate one embodiment of the invention, Figure 1 representing a sectional view of the platen press, Figure 2 shows the transfer cylinder in the lower position, while Figure 3 shows the

transfer cylinder in the upper position. The form 13 is arranged above the path of the platen and the elastic flat form 14 is arranged on the printing level of the platen 11 so that the latter will be pressed against it when it is brought into printing position. The form 13 is inked by means of the to-and-fro moving inking rollers 5 which in turn are being moved by the lever arrangement 60, 61, 62. The transfer of the printing picture from the form 13 to the elastic flat form 14 is effected by means of the transfer cylinder 6 which, through the lever arrangement 63, 64, 65 is moved to-and-fro over both forms. The transfer cylinder 6 and the flat form 14 are covered with elastic material, preferably rubber. The annular circumference of the transfer cylinder has an incision 66 which during the to-and-fro movement of the transfer cylinder over the ink rollers 67 is in such a position to cover the ink roller 67. In this manner the transfer cylinder 6 can easily roll over the ink roller 67 without touching it.

In the position for laying-on the sheets 75 wherein the press is shown in the drawing the transfer cylinder 6 is shown at the lower end of the flat form 14, the inking rollers 5 lie on the ink roller 67 and receive ink from the latter: As soon as the platen 11 begins 80 to get into printing position, the rollers pass over the forms 14 and 13 into the position shown in dotted lines 6^a, 5^a. The inking rollers 5 are then in the position indicated by 5^a upon the ink rollers 33 of the inking arrangement 85 and are now supplied there with ink.

In the meantime the platen has gone into printing position by pressing itself against the elastic, flat form 14. If the platen has 90 finished its printing action, the transfer cylinder 6 passes from the position 6^a over the form 13 and takes off from the latter, in form of an impression, the ink previously supplied by the inking rollers, bridges with 95 its incision 66 the ink roller 67, enters then upon the elastic form 14 and transmits its impression to the latter, until it arrives at the lower position 6 where it reverses its movement in the opposite direction. 100

Through this transfer the impression will appear on the elastic flat form 14 as reflected image and after the image has been transferred to the working sheet it will appear as the true, positive impression.

Simultaneously with the roller 6 the inking rollers 5 are moved from their position 5^a and pass over the form 13 which they ink and run then upon the ink roller 67. Here they remain for a short time, rotate through friction with the ink roller 67 and are supplied with ink by the latter. With this fresh supply of ink they ink again the form 13 on their return trip to the inking arrangement 33, 34. The circumference of the inking rollers is large enough to permit just one rotation during its passage over the form 13 whereby uniform inking without the formation of any stripes is assured.

For the purpose of receiving ink the inking rollers 5 remain stationary for a short time over the ink rollers 33 and 67 and the to-and-fro movement of the lever arrangement 60, 61, 62 is arrested for the same period when the cranks are reversed. This is effected by means of the spur wheel 8 which is equipped with teeth on parts of its circumference and whose toothless parts always cause during rotation a short stop of the cog wheel 68 driven by it. Spur wheel 8 together with spur wheel 38 is mounted on the main shaft 9 to both ends of which are also attached the cranks 10 which by means of the connecting rods 10^a effect the movement of the platen 11. The two spur wheels 8 and 38 rotate therefore in the same manner as the cranks 10 of the connecting rods. Spur wheel 8 engages with the crank wheel 68 whose cranks 69 operate the rod 60 with lever arm 61 and the guide rod 62 with the linked-on carrier 70 of the inking rollers 5.

As the spur wheel 8 has two toothless spots arranged opposite each other, it drives the crank wheel 68 at the toothed parts only while the crank wheel 68 remains stationary during the passage of the toothless spots in order to cause the lever arrangement 60, 61, 62 and the linked-on carrier 70 of the inking rollers 5 to occupy always in the moment of stopping the position on the ink rollers 33 or the ink roller 67.

The spur wheel 38 engages with the equally large crank wheel 71 and actuates by means of the crank 79 the lever arrangement 63, 64, 65 and the linked-on carrier of the roller 6 in such a manner that the roller 6 at each turn of the wheel is led once to-and-fro over the forms 13 and 14.

As a repeated transfer is not desirable the transfer cylinder 6 must carry out one of its two movements, i. e. either the forward or the backward movement, without touching the forms 13 and 14. The constructive example shown here exhibits the transfer

cylinder in raised position during its movement from the lower position 6 to the upper position 6^a. As lifting device serves f. i. a wedge 72 (Figs. 2-3) arranged under the elastic sliding bearing 72^b of the transfer cylinder 6; this wedge can slide to the right or left and cause thereby a raising or lowering of the transfer cylinder 6. If the wedge 72 is moved to the right (Fig. 2), the sliding bearing 72^b will be raised by sliding on the inclined plane of the wedge 72 and the transfer cylinder 6 will maintain a certain distance from the forms 13 and 14. If, on the other hand, the wedge is pushed to the left as indicated in Fig. 3, the sliding bearing will be lowered and the transfer cylinder 6 touches on its return trip the forms 13 and 14. The moving of the wedge 72 is effected by means of adjustable stops 73, 74 provided at both ends of the roller path; these stops are touched by extensions on the right and left end of the wedge 72. The lifting device can also consist of any other suitable mechanism.

Having now described the nature of my invention and how the same may be performed, what I claim and desire to secure through Letters Patent is:—

1. In improvements of platen presses the combination of a platen, a form arranged above the path of the platen, an elastic flat form situated on the printing level of the platen and to-and-fro moving inking rollers; means of moving them over the form, and a transfer cylinder, also means of moving this transfer cylinder over the elastic flat form and the form and an inking arrangement, exactly as described.

2. In improvements of platen presses the combination of a platen, a form arranged above the path of movement of the platen, an elastic flat form situated on the printing level of the platen, to-and-fro moving inking rollers, a system of levers adapted to move the inking rollers over the form, and a transfer cylinder and levers adapted to move the transfer cylinder over the form and the elastic flat form the transfer cylinder transmitting the printing picture from the form to the elastic flat form, also means of causing the platen to make alternate movements corresponding to the upward and downward movement of the inking rollers and the transfer cylinder in such a manner that the printing action takes place after the passage of the transfer cylinder over the elastic form and during the inking of the form by means of the inking rollers, exactly as described.

3. In improvements of platen presses the combination of a platen, a form, an elastic flat form, inking rollers and a transfer cylinder positioned in a sliding bearing; also a mechanism adapted to lift the transfer cylinder off the form and the elastic flat

form during one to-and-fro movement so that during one forward movement the transfer cylinder remains out of touch with the flat elastic form and the printing form while 5 during its return trip the contact is re-established, or vice versa, exactly as described.

In testimony whereof I affix my signature in presence of two witnesses.

EDUARD GROSSE.
